UNITED STATES PATENT OFFICE.

WINFIELD L. HENSEL, OF AKRON, OHIO, ASSIGNOR TO THE MILLER RUBBER COMPANY,
OF AKRON, OHIO, A CORPORATION OF OHIO.

DISPLAY DEVICE FOR WATER BOTTLES.

Application filed January 21, 1927. Serial No. 162,511.

My said invention relates to an advertising or display device for use in connection with rubber water bags or hot water bottles as they are customarily termed.

5 The invention aims to provide a simple and economical attachment which may be readily applied to the bag prior to its being placed in its display carton for shipment and which will retain its position thereon and 10 which, when supplied with the customary advertising matter such as maker's name, or (and) trade-mark, price, etc., will present a distinctive and unique appearance.

With these and other objects in view the 15 invention includes the novel article herein-after described and defined by the appended claims.

In order that the invention may be better understood, I have shown it in the accompanying drawings in connection with a water bag located in its display carton, it being understood that these bags are packed for the trade in individual boxes or cartons in which they may be displayed in store windows and the like by removal of the cover.

25 In this drawing:

Figure 1 is a plan view of the box with the bag or bottle therein carrying the display device or corner.

30 Fig. 2 is a plan view of the blank from which the display device is made, and

Fig. 3 is a sectional detail.

Referring by reference characters to this drawing the numeral 1 designates the carton 35 which is merely a tray like box adapted to receive the customary cover (not shown). The bottle indicated by the numeral 2 is of customary form and is provided at top and bottom with apertured tabs 2^a and 2^b, the 40 apertures of which are engaged by buttons or studs 1^a and 1^b respectively affixed to the bottom of the box.

The display device or corner comprises a 45 pair of substantially triangular sheet members or portions 3 and 3^a having their side and bottom edges which are disposed in substantially triangular relation, connected by side and bottom cross webs or portions 3^b.

This forms a substantially triangular 50 pocketed member which can be slipped onto the corner of the bag and forms an attractive and unique display device, the top member

having printed thereon advertising or other desired material.

Preferably this member 3 is provided with 55 an integral triangular extension 3^a which, together with the adjoining portion of the top member is printed to simulate a label as shown.

The bottom cross web 3^c is provided with 60 a slot 3^e to receive the bottom tab 2^b, the closed end of the slot serving to prevent the device from slipping off the bag.

I preferably make the device or "corner" 65 from a single blank cut to the shape shown in Fig. 2, which is scored on lines b b' and c c' to form lines of fold.

The portion 3^f of the blank below the fold line c' is designed to overlap the lower edge 70 of the member 3^a and is provided with a tongue 3^g adapted for insertion in the slot a of member 3^a. Preferably the tongue has an enlarged portion as shown and a slot g which enables the two parts formed thereby to be overlapped, thereby narrowing the 75 head of the tongue sufficiently to enable it to be inserted in the slot a whereafter it expands and is locked in place.

The edges 3^h and 3ⁱ between the adjacent ends of the cross webs are preferably 80 rounded to conform to the curved corner of the bag.

I claim:

1. A advertising attachment for water bottles comprising spaced parallel sheet 85 members having side and bottom edges disposed in substantially right angular relation and cross webs connecting said side and said bottom edges respectively, said members and cross webs being formed from 90 a single sheet of material, and said bottom cross web having an integral extension overlying the edge of the member at the back of the bag, said back member having a slit and said extension a tongue engaging the 95 slit.

2. The device of claim 1 in which the tongue has an enlarged head and a central slit permitting contraction of the head.

3. An advertising attachment for water 100 bottles comprising a pair of parallel sheet members of substantially the shape of a right angle triangle, and cross webs connecting the side and bottom edges of the respec-

tive sheets leaving the space between the diagonal edges unobstructed, one of said cross webs being detachably connected to one of said sheets and being provided with 5 an elongated slot open at one end.

4. An advertising attachment for water bottles comprising a pair of parallel sheet members, each of which is of substantially the shape of a right-angle triangle, a cross

web integral with both members and connecting the side edges thereof, and a cross web connecting the bottom edges, said last named cross web being integral with one of said members and having means for detachable connection with the other member. 10 15

In testimony whereof, I affix my signature.

WINFIELD L. HENSEL.
